LIMIT SWITCH

Gale K. Carlson, Dixon, Ill.

Application October 28, 1950, Serial No. 192,677

4 Claims. (Cl. 200—47)

1

My invention relates to limit switches. More particularly, my invention relates to an improvement in limit switches whereby the same are made simply and accurately adjustable. My invention has particular utility as an electric door operator, such as an overhead garage door operator.

It is an object of my invention to produce a simply constructed limit switch with a minimum of movable parts, which is, nevertheless, fully adjustable. It is another object of my invention to develop a limit switch mechanism in which each limit is separately and accurately adjustable. It is a further object of my invention to provide a means of adjusting a limit switch which does not involve the necessity of opening the case containing the limit switch nor the necessity of shutting off the current to the switch. It is a still further object of my invention to produce an adjustable limit switch which will hold its precise setting without the necessity of using lock nuts or similar fastening means. Other specific objects and advantages will appear as the specification proceeds.

In general, my invention, which substantially achieves the above objects, comprehends the making of the switches movable by pivotally mounting the switches and associating therewith a threaded adjusting rod. My invention also involves the placement of the adjusting rod in tension by placing a compression spring thereon. In addition, my invention includes extending the adjusting rods beyond the base of the limit switch and adapting the end portion of the adjusting rod so that they may be easily turned.

My invention is illustrated, in a preferred embodiment, by the accompanying drawing in which—

Fig. 1 is a plan view of my adjustable limit switch showing the structure below the base as hidden objects; Fig. 2 is a broken bottom view showing a portion of the structure above the base as hidden objects; Fig. 3 is a broken side elevational view taken in section on line 3—3 of Fig. 2; and Fig. 4 is a perspective view of the parts forming the adjusting rod and switch prior to assembly.

In the various figures of the drawing, like reference numbers designate like parts.

It will be understood that the structure of the left and right switches together with their adjusting rods is identical. For purposes of simplicity of description, however, the reference numbers have been made to refer only to the

switch on the right in Fig. 1 which is shown on the left in Fig. 2.

In the illustration given, 1 designates a frame or base formed of a suitable metal or other material having attached thereto a threaded shaft 14, rotating in bearings 19, and having traveling thereon operating nut or member 16. Operating nut 16 is equipped with guide finger 17 which rides on guide shaft 15 and contact finger 18 which extends in the other direction. A gear or sprocket 13 is attached to the end of threaded shaft 14 whereby the shaft may be caused to rotate, as for example, by an electric motor. It will be apparent that other means for actuating shaft 14 can be used, such as a slip-on coupling with a threaded shaft.

Block 2 is pivotally mounted on frame 1 by pivot screw 3 which is fastened below frame 1 by nut 4. If desired, a washer or other device 20 can be used to make block 2 more easily rotatable, or a pin may be used instead of a screw. Mounted on block 2 is a switch, preferably a micro-switch, having terminals 7, stationary contact 5, and movable contact arm 6. If a micro-switch is used as I prefer, a very slight pressure on contact arm 6 is sufficient to actuate the switch. Since the details of micro-switch construction are well known, it is not believed necessary to further elaborate them here.

Sliding pin or screw 8 is located at the other end of block 2 from pivot screw 3. Sliding pin 8 is secured in block 2 and extends through the curved or arcuate slot 9 in frame 1. Beneath frame 1, sliding pin 8 is secured into dog 12. Threaded adjusting rod 10 having screw head 21 extends through end flange 20 of base 1 and threadedly engages dog 12. Compression spring 11 is located on adjusting rod 10 between end flange 20 and dog 12. It is apparent that the exterior end of adjusting rod 10 now shown as screw head 21 can be modified in various ways to facilitate the turning of adjusting rod 10, such as by forming thereon a knurled nob or a head shaped to fit a wrench.

By inserting a screw drive in screw head 21, adjusting rod 10 may be rotated in either direction, thus causing dog 12 to respectively advance or retreat upon adjusting rod 10. This motion of dog 12 is communicated by sliding pin 8 riding in curved slot 9 to block 2, and thereby causes block 2 to pivot on screw 3. The pivoting of block 2 produces a displacement of movable contact 6, since it is secured to block 2. Compression spring 11 holds adjusting rod 10 in tension, and

thereby provides for the maintaining of the exact setting of movable contact 6.

The rotation of threaded shaft 14 by gear 13 causes operating nut 16 to travel to the right as viewed in Fig. 1. After a predetermined number of revolutions, contact finger 18 of operating nut 16 will engage movable contact 6 and press against it. This pressure will be transmitted to contact 5, and will thereby close an electric circuit inside of the micro-switch and stop the rotation of shaft 14.

The switch on the left in Fig. 1 operates in exactly the same way as the switch on the right which has just been described. Its purpose is to limit the transversing of the operating member to the left on threaded shaft 14. Thus the movable contact arms of the two switches limit the travel of operating nut 16 in either direction at a predetermined point selected by turning the adjusting rods.

While in the foregoing specification I have shown my limit switch structure in great detail and in a specific arrangement for illustration, it will be understood that such arrangement and details of the structure may be varied widely by those skilled in the art without departing from the spirit of my invention.

I claim:

1. In a switch mechanism characterized by an operating nut traveling on a rotatable threaded shaft, a frame with two blocks pivotally mounted thereon over arcuate slots in said frame, switches including movable contact arms secured to said blocks, said arms positioned to engage said operating nut when said nut has traveled a predetermined distance in either direction, dogs secured to said blocks by pins through said slots, and adjusting rods having a compression spring thereon threadedly engaging said dogs, said rods extending outside of said frame, and terminating in turning means, whereby said rods can be turned and thereby position said movable contacts to limit the travel of said operating nut.

2. An adjustable limit switch comprising a base aligned with a threaded shaft traversed by an operating member upon rotation of said shaft, two electric switches rotatably connected to said base, said switches including movable arms positioned to alternately contact said operating member upon traversing a predetermined

distance in either direction, and adjusting rods under spring tension threadedly rotating said switches, whereby said movable arms can be positioned to engage said operating member at a selected point on its line of traverse in each direction.

3. An adjustable limit switch comprising a base, a threaded shaft mounted in bearings attached to said base, a guide shaft aligned with said threaded shaft, an operating nut traveling on said threaded shaft, said nut including a guide finger resting on said guide shaft and a contact finger extending in the other direction, two blocks pivotally mounted over curved slots in said base, micro-switches secured to said blocks, said switches including movable arms positioned to engage said contact finger when said finger has traveled a predetermined distance in either direction, dogs secured to said blocks by pins extending through said slots in said base, and rods including a compression spring thereon threadedly engaging said dogs, said rods extending beyond said frame and terminating in a turning adaptation, whereby said rods can be turned and thereby rotate said blocks to separately position said contact arms.

4. An adjustable limit switch comprising a base adjacent to a threaded shaft traversed by an operating member upon rotation of said shaft, two electric switches rotatably connected to said base, said switches including arms adapted to actuate said switches when pressure is applied thereto and being positioned to be alternately contacted by said operating member upon said operating member traversing a predetermined distance in either direction, and adjusting rods threadedly rotating said switches, whereby said arms can be positioned to engage said operating member at a selected point on its line of traverse in either direction.
